LOOM FOR WEAVING

Jakob Wolfensberger, Bauma, Switzerland

Application January 9, 1936, Serial No. 58,429
In Switzerland January 16, 1935

1 Claim. (Cl. 139—191)

This invention relates to a weaving loom with a stationary frame.

According to the invention the beating-up comb thereof is mounted between the ends of 5 thrust rods each of which is jointed at one end to a rotary crank and has its other end mounted in floating manner, and one of the longer sides of the resulting substantially ovoid or pear-shaped path which the operative part of the 10 comb follows in making a beating-up movement is arranged to lie within the zone of the shed.

The invention provides, therefore, a simple 15 means whereby the comb makes its beating-up strokes in the shed and its return strokes in a path lying outside the shed zone so that weft can be laid during the return movements, the time available for the laying being increased or it being possible to run the loom faster than has generally been the case hitherto.

20 The shuttle track is preferably formed by a rake and the reed of the stationary slay which also provides a lateral guide for the prongs of the beating comb.

The invention will now be described with reference to the accompanying drawing, wherein:

25 Fig. 1 shows a diagrammatic cross section of the weaving machine;

Fig. 2 shows a diagrammatic plan (beating comb in the beating-up position);

30 Fig. 3 shows a modification of the suspension for the thrust rods in adjustable sliding guides.

The reed 2 is connected to the stationary slay 1. The shuttle track consists of a rake in the form of guide plates 3 which are secured at one 35 end in the transverse member 4 and which with the other ends reach up to dents of the reed 5. The shuttles used may be of any standard shape. The thrust rods 6 are reciprocated by the crank pins 7 and rock with their front ends on rocking levers 8. Between the ends of the thrust rods 40 6 is secured the beating comb 9 with the beating prongs 10. Each prong 10 slides between two guide plates 3 without completely leaving these. A shedding device 11, 12, 13, 14 and 15 of any 45 known and suitable construction is arranged in the usual manner. The shedding motion forming no part of the invention is shown only in a diagrammatical manner.

The suspension of the thrust rods 6 may, for 50 example, also be effected as shown in Fig. 3. The sliding guide 17 is secured to the shield 13. The screw 20 which is located in the curved slot 17', enables the sliding guide 17 to be moved through a predetermined amount and firmly 55 clamped. 19 is the sliding block in which the

thrust rod 6 is mounted and which moves in the sliding track 17'. By this device a variation of the path described by the beating-up comb 9 is rendered possible.

The method of operation is as follows.

By turning the crank shaft 1, the beating-up comb 9 describes with the upper ends of the prongs, a substantially pear-shaped or ovoid curve 10' of which the point is located at the beating edge 11' of the woven material. By 10 means of shuttles 16, the track of which being formed by the reed and the rake, a weft is inserted when the shed is open. At the moment the shuttle passes out of the shed the crank pins 1 have reached the rear dead centre, the beating 15 prongs 10 being in the position before fully entering the shed. Simultaneously, however, the shed commences to change and the points of the beating prongs 10 are able to follow the lower warp during the upward movement up to the 20 middle, that is to say, until the two warps meet. The weft thread is located and held between the warp threads and is now beaten-up by the comb 9 or beating-up prongs 10, while the shed continues to change completely. The points of the 25 prongs pass closely over the dents of the reed, the weft is caught by the prongs without fail immediately after the descending upper warp has crossed into the comb. Already before the 30 front dead centre of the crank is reached (beating position shown in chain dotted lines in Fig. 1) the shed may be opened to such an extent that the shuttle may again enter. It then has available the period of time corresponding to 35 half a revolution of the crank shaft for traversing the warp, that is to say, until shortly before the rear dead centre is reached. It is thus possible to provide for the shuttle about half the time of operation more than is possible in an ordinary 40 loom. In other words: with the same time of movement of the shuttle, the crank shaft may move about 50% faster. During the return 45 movement the beating comb, after the completion of the beating, is lowered and then leaves the shed. It then again moves upwardly closely along the reed 2 when the crank approaches its rear dead centre. In the meantime, however, the fresh weft has been inserted and the operation is repeated.

The present construction thus permits of obtaining a considerable increase in efficiency as compared with the usual methods. The warp material receives an extremely careful treatment, as it is only combed in one direction.

What I wish to secure by U. S. Letters Patent
is:

In a weaving loom having a shed, a stationary
rake, a beating-up comb, thrust rods between the
ends of which said comb is mounted, a shaft hav-
ing rotary cranks to which one end of each of the
respective thrust rods is connected, pivoted links

to which the other end of each of the respective
thrust rods is connected, in virtue of which the
operative end of the prongs of said comb is caused
to move in a pear-shaped path in making a
beating-up movement, the path lying within the
zone of the shed. 5

JAKOB WOLFENBERGER.
